APPENDIX

UNITED STATES PATENT OFFICE.

EDWIN S. PRIDHAM, OF SAN FRANCISCO, CALIFORNIA, ASSIGNOR TO COMMERCIAL WIRELESS & DEVELOPMENT CO., OF SAN FRANCISCO, CALIFORNIA, A CORPORATION OF ARIZONA.

*TELEGRAPHIC SENDING-CIRCUIT.

1,276,412.

Specification of Letters Patent. Patented Aug. 20, 1918.

Application filed August 22, 1916. Serial No. 116,252.

To all whom it may concern:

Be it known that I, EDWIN S. PRIDHAM, a citizen of the United States, residing at the city and county of San Francisco and State of California, have invented new and useful Improvements in Telegraphic Sending-Circuits, of which the following is a specification.

In large radio stations where considerable amounts of energy are handled in the key circuits for signaling, a great amount of trouble has been experienced with the contacts of controlling keys on account of the intense arcing when the contacts are opened. This has been of especial trouble in those systems where the energy of the antenna circuit is directly changed or interrupted as in those stations using undamped waves generated from a direct current source. As with all forms of electric circuits the most trouble is experienced in opening the circuit, that is, in drawing two closed contacts apart. A negligible amount of sparking takes place on closing the circuit.

The main object of the present invention is to prevent the sparking at the reciprocating contacts on the breaking of the circuit. The method of doing this is to shunt the closure of the circuit, immediately before the opening of the contacts, to a brush and rotating commutator arrangement so that when the brush slips off the conducting segment of the commutator the arcing takes place there.

Since the area of contact between the brush and the commutator conducting segment and the length of the insulating gap may be made as large as desired it will be apparent that the arcing will do far less damage under this arrangement than with reciprocating contacts.

It should be noted that the function of the rotating commutator is only to break the current when the circuit is shunted to it and it has no function in determining a dash or dot.

There is no synchronism between the sending key and the rotating commutator and it is only necessary that the speed of rotation be such that when the sending key is raised a break will be made on the commutator before the key can be again depressed. The means whereby this result is successfully ac-

complished are shown in the accompanying drawings and explained in the following description:

Figure 1 shows a diagrammatic view of a preferred form of the device embodying my invention.

Fig. 2 shows a diagram of a modified arrangement of the same.

In the preferred form of the device a main circuit 10, in which is included the source of energy to be varied such as a shunted portion of the transmitting helix of an arc generator circuit, has the spaced terminals 11. These terminals 11 can be opened and closed by means of a contact piece 12 mounted on the armature 13 of the relay 14. The relay 14 is connected in the local circuit 15 in which is included the battery 17 and the key 16.

In parallel with the main circuit 10 is an auxiliary circuit 18 which will hereinafter be termed the main auxiliary circuit, included in which is a pair of spaced terminals 19 and the rotating switch A. A contact piece 20 on the armature 21 of a second relay magnet 22 is adapted to close the terminals 19. The relay magnet 22 has an energizing circuit 23 including the battery 17 and in which is a pair of spaced terminals 24 adapted to be closed by the contact piece 25 on the armature 13.

The rotating switch A comprises the rotatable shaft 26, carrying a conducting ring 27 with which a stationary brush 28 contacts, and a conducting segment 29, electrically connected to the ring 27 and adapted to be engaged by a stationary brush 30 and an insulating segment 31 coöperating with the conducting segment.

Consider the operation of the device for closure of the main circuit 10. All the circuits are open and the commutator is running at an arbitrary speed of 30 revolutions per second. The hand key 16 is depressed, the first relay 14 is energized which brings down the armature 13 and the terminals 11 are closed by the contact piece 12.

As soon as armature 13 comes down, terminals 24 are closed by contact piece 25 and thus the relay 22 is energized by current from battery 17 thereby closing terminals 19 by contact piece 20. The terminals 19 form a part of the main auxiliary circuit 18.

As soon as a conducting segment 29 comes under the brush 30 the main auxiliary circuit is completed and is in parallel with the main circuit 10.

5 Since the commutator is running at a high speed it will be seen the two circuits respectively to terminals 11 and 19 are closed practically simultaneously. Thus the main circuit 10 is closed directly at 11 and intermittently through the commutator at 19. However, it will be understood that as long as the terminals 11 are directly short circuited by contact piece 12, the intermittent action of the commutator will have no effect on the 15 signals.

The hand key 16 controls the duration of the short circuit of terminals 11, be it for a dot or a dash, except for a very short interval of time when the hand key is raised.

20 During this interval the short circuit is transferred to the conducting segment 29 and brush 30 of the main auxiliary circuit 18, the circuit at 11 is opened without spark and then the rotation of the commutator 25 breaks the main auxiliary circuit when the conducting segment passes under the brush 30.

For the successful operation of the transmitting device which is the subject of this 30 specification, it is necessary that the release of the relays 14 and 22 be controlled in relation to the closure and breaking of the main auxiliary circuit by the brush 30 and conducting segment 29 so that the only sparking 35 takes place on the commutator.

For this purpose there are auxiliary controlling circuits for the relays 14 and 22 which are respectively associated with switches which are definitely spaced in relation to the rotating commutator in the main auxiliary circuit and are mounted on the same shaft with the rotating commutator.

An auxiliary energizing circuit for relay 14 includes the battery 17, the brush 35, ring 45 36, segment 33, brush 37 and the spaced terminals 24. It will be seen that if the relay arm 13 has been brought down by closing of the hand key 16, then this circuit is active whenever brush 35 is in contact with segment 33, but not otherwise, as the terminals 24 are open when relay arm 13 is in release position. The function of the auxiliary circuit for relay 14 is to prevent the release of armature 13 while brush 30 of the main auxiliary circuit is on an insulating segment. Thus, if the key 16 is released the relay magnet 14 will still be energized until the main auxiliary circuit brush 30 is in contact with segment 29 when relay 14 will be deenergized by brush 35 breaking contact with segment 33.

Relay magnet 22 likewise has an auxiliary energizing circuit, including the battery 17, the spaced terminals 39, brush 43 and con-

ducting segment 41 of the rotating switch C. 65

As long as relay arm 13 is down, relay magnet 22 is energized through the circuit including battery 17 and spaced terminals 24. Now when relay arm 13 releases, as hereinbefore described, it is necessary that terminals 19 remain closed until brush 30 is out of contact with segment 29 of the main auxiliary circuit, that is, until the main auxiliary circuit is broken. Then the auxiliary circuit for relay magnet 22 is broken by brush 43 passing out of contact with segment 41. It will be seen that segment 41 is carried some distance beyond segment 29, thus giving the main auxiliary circuit space enough to be completely broken before relay arm 21 rises and opens the terminals at 19. As the rotation of the switching commutators is at the rate of about 30 per second, the sequence of operations is very rapid and as far as the operator handling the key 16 is concerned, he is controlling the signals as usual.

The spaced terminals 24, 39 and 19 are so arranged as shown in relation with the relay arms 13 and 21 that the circuits in which these spaced terminals are included can only be active when the relay arms are down, otherwise the rotation of the commutators would intermittently energize the relays. As shown in the figures, the respective commutator switches only operate to release the contacts after the relay arms 13 and 21 have initially been brought down by the operation of key 16. As hereinbefore stated, the hand key controls the duration of closure of the main circuit except for that short period of time occupied by the respective commutator segments to pass under the brushes.

The operation of the device is as follows: When the hand key 16 is depressed, current from the battery 17 flows through the circuit 15, energizing the relay magnet 14 and causing the armature 13 to come down, thus closing the terminals 11 and 24.

The closing of terminals 11 completes the main circuit 10, whereby to despatch signals. The closing of terminals 24 completes the circuit 23 which includes the battery 17 and the energizing coil of relay 22, thereby bringing down armature 21 and closing terminals 19 and 39.

The closing of terminals 19 permits the main commutator A with its brush 30 to be operative in the main auxiliary circuit, as hereinbefore stated. As long as the terminals 11 are closed the making and breaking of the main auxiliary circuit has no effect on the signaling. At any moment when the main auxiliary circuit is complete by brush 30 being on conducting segment 29, the terminals 11 can be opened without spark. Thus it is necessary to prevent the deenergizing of relay 14 until the main auxiliary

circuit is complete. For this purpose an auxiliary energizing circuit is supplied for relay magnet 14. This circuit includes a rotating commutator B (on the same shaft 5 with A) whose conducting segment 33 is oppositely disposed in relation to the main conducting segment 29 and occupies an equal angular distance with the exception that commutator segment B slightly overlaps the insulating part of commutator C. If the key 16 is raised at an instant of time when the main auxiliary circuit is open on account of brush 30 being on insulating segment 31, the contact 11 will remain closed 15 since the auxiliary circuit for relay 14 is complete through circuit 17, 15, 32, 35, 33, 36, 37, 32, 24, 23, 17. And relay 14 will remain energized until brush 35 slips off segment 33 when relay 14 will be deenergized. 20 Terminals 11 can then open without spark.

When relay 14 is deenergized and relay arm 13 rises, thus breaking terminals 24 and breaking the circuit through 17, 23, 24, 23, 23, 17 in which is included the relay 22, 25 it is necessary to provide an auxiliary energizing circuit for relay 22, which will keep relay 22 active, thus maintaining the closure of terminals 19 until the main auxiliary circuit has been broken by brush 30 slipping 30 off commutator segment 29. Then terminals 19 can be opened without spark. For this purpose an auxiliary energizing circuit for relay 22 is supplied. This circuit includes a rotating commutator C on the same 35 shaft with the main commutator A. The conducting segment 41 is definitely spaced in relation to main commutator segment and extends some distance beyond it so that when brush 30 is on segment 29, brush 40 43 is on segment 41 and remains on 41 until brush 30 passes completely off segment 29.

When relay 14 is deenergized by brush 35 slipping off 33, and terminals 24 are opened, relay 22 will be energized through 45 the circuit 17, 23, 39, 38, 44, 45, 41, 43, 38, 28, 17 and will remain energized until brush 43 is out of contact with segment 41. Thereupon relay arm 21 will rise breaking terminals 39 and preventing the relay 22 50 from again being energized by the rotation of the commutator C until it has again been brought down by the operation of relay 14. Likewise when terminals 24 are broken, the successive closing of switch B will not cause 55 a reenergization of relay 14. If this precaution were not taken, signals would be sent out intermittently by the rotation of the switches.

However, the associated switches can only 60 energize their respective relays during one engagement of their conducting segments with the brushes following the release of the telegraphic key 16.

This period of time can be so shortened

by speeding up the rotation of the commutators that the momentary prolonging of the closure of the main circuit 10 will have a negligible effect on the signaling; the prolongation being far shorter than the period of time represented by a dot. While it is 65 stated that the speed of the associated commutators, is 30 revolutions per second, it will be understood that this certain speed is not essential to the efficient operation of the device. 75

By causing the arcing or sparking to occur on the heavy commutator segment the contacts for controlling the main sending circuit are saved and the danger of fusing 80 is overcome.

The end of the main conducting segment A will be worn and burnt in time and I prefer to make them removable so that they may be replaced as occasion requires.

In Fig. 2 the arrangement is substantially 85 the same throughout, with the exception that the second relay 22 has its initial energizing circuit 23 controlled directly by key 16, and additional contact 16^a being provided for the purpose. 90

While I have shown and described herein two specific forms of my invention, it will be understood, nevertheless, that the same is susceptible of other modifications and that many changes in construction and arrangement of the several parts may be employed without departing from my invention as disclosed in the appended claims. 95

Having thus described my invention, what I claim and desire to secure by Letters Patent is— 100

1. In a telegraphic sending circuit, a main circuit provided with spaced terminals by the opening and closing of which the main circuit is directly opened and closed and signals are despatched, an auxiliary circuit shunted around said terminals, said auxiliary circuit including an automatic switch in series with spaced terminals by the closing of which said automatic switch is operative to make and break said auxiliary circuit. 105

2. In a telegraphic sending circuit, a main circuit provided with spaced terminals adapted to be opened and closed for the direct despatch of signals in combination with an auxiliary circuit shunted around said main circuit, terminals, said auxiliary circuit including in series connection a rotating switch and spaced terminals by the closing of which said rotating switch is automatically operative to open and close said auxiliary circuit. 115

3. In a telegraphic sending circuit, a main circuit provided with spaced terminals, operating means for the closure of said terminals whereby said main circuit is directly closed for signaling purposes, an associated 120

- circuit in shunt on said main circuit, said associated circuit including in series connection spaced terminals and a rotating switch, and means automatically operative on the closure of said main circuit terminals for closing the terminals of said associated circuit.
4. In a telegraphic sending circuit, a main circuit provided with spaced terminals, means for initiating the closure of said terminals to directly close said main circuit, an associated circuit including spaced terminals and a rotating switch in series connection shunted around said main circuit terminals, automatic means operative on the closure of said main circuit terminals to close said associated circuit terminals whereby said rotating switch is operative to make and break said associated circuit, and automatic means co-acting with said rotating switch to maintain the closure of said main circuit terminals until said associated circuit is closed by said rotating switch.
5. In a telegraphic sending circuit, a main circuit provided with spaced terminals, initial operating means for the closure of said terminals, an associated circuit including spaced terminals and a rotating switch in series connection shunted around said main circuit terminals, automatic means operative on the closure of said main circuit terminals to close said associated circuit terminals whereby said rotating switch is operative to make and break said associated circuit, and automatic means co-acting with said rotating switch to maintain the closure of said associated circuit terminals until said associated circuit is broken by said rotating switch.
6. In a telegraphic sending circuit, a main circuit provided with spaced terminals, key controlled means for operating a relay to initiate and maintain a direct closure of said main circuit terminals, an auxiliary circuit including spaced terminals and a rotating commutator in series connection shunted around said main circuit terminals, a second relay to initiate and maintain the closure of the spaced terminals of said auxiliary circuit, said second relay being initially controlled and maintained by the closure of said first mentioned relay, an automatic switch synchronously rotating with said auxiliary circuit commutator by means of which the closure of said first mentioned relay is maintained in the event of the release of the key controlled means.
7. In a telegraphic sending circuit, a main circuit provided with spaced terminals and a relay operated contact for directly closing said terminals for initiating a signal, an auxiliary circuit in shunt around said terminals, said auxiliary circuit including spaced terminals and a rotating commutator in series connection, a second relay operated contact for closing the terminals of said associated circuit, the closure of the second relay operated contact being initiated and maintained by the closure of the first relay and means co-operating with said rotating commutator to prolong the closure of the second relay operated contact after the first relay operated contact is released, said means including a rotatable switch.
8. In a telegraphic sending circuit having spaced terminals, a relay, a key-controlled local circuit for operating the relay, a contact operated by the relay for closing the main sending circuit, an auxiliary circuit in shunt with the main sending circuit, a second relay, a contact operated by the second relay for closing the auxiliary circuit, a primary energizing circuit for the second relay closed by a contact operated by the first relay when the latter is energized, an intermittent switch included in said auxiliary circuit, and a secondary energizing circuit for the second relay closed by the closure of the auxiliary circuit, whereby the auxiliary circuit will remain closed independently of the release of the first mentioned relay-operated contact and will be broken by said switch.
9. In a telegraphic sending circuit having spaced terminals, a relay, a key-controlled local circuit for operating the relay, a contact operated by the relay for closing the main sending circuit, an auxiliary circuit in shunt with the main sending circuit, a second relay, a contact operated by the second relay for closing the auxiliary circuit, a primary energizing circuit for the second relay closed by a contact operated by the first relay when the latter is energized, an intermittent switch included in said auxiliary circuit, a secondary energizing circuit for the second relay closed by the closure of the auxiliary circuit, whereby the auxiliary circuit will remain closed independently of the release of the first mentioned relay-operated contact and will be broken by said switch, and an intermittent switch included in said secondary energizing circuit and operable to break said circuit following the breaking of the auxiliary circuit.
10. In a telegraphic sending circuit having spaced terminals, a relay, a key-controlled local circuit for operating the relay, a contact operated by the relay for closing the main sending circuit, an auxiliary circuit in shunt with the main sending circuit, a second relay, a contact operated by the second relay for closing the auxiliary circuit, a primary energizing circuit for the second relay closed by a contact operated by the first relay when the latter is energized, a secondary energizing circuit for the first relay closed by a contact on the armature of said relay, whereby to insure energization of said relay in the event of failure of the key-controlled circuit, and an intermittent switch included in said secondary energizing circuit.

included in said auxiliary circuit for breaking the same at a point removed from the relay-controlled contacts.

11. In a telegraphic sending circuit having spaced terminals, a relay, a key-controlled local circuit for operating the relay, a contact operated by the relay for closing the main sending circuit, an auxiliary circuit in shunt with the main sending circuit, a second relay, a contact operated by the second relay for closing the auxiliary circuit, a primary energizing circuit for the second relay closed by a contact operated by the first relay when the latter is energized, a secondary energizing circuit for the first relay closed by a contact on the armature of said relay, whereby to insure energization of said relay in the event of failure of the key-controlled circuit, an intermittent switch included in said auxiliary circuit for breaking the same at a point removed from the relay-controlled contacts, and an intermittent switch included in said secondary energizing circuit for breaking the same prior to the breaking of the auxiliary circuit by its switch.

12. In a telegraphic sending circuit having spaced terminals, a relay, a key-controlled local circuit for operating the relay, a contact operated by the relay for closing the main sending circuit, an auxiliary circuit in shunt with the main sending circuit, a second relay, a contact operated by the second relay for closing the auxiliary circuit, a primary energizing circuit for the second relay closed by a contact operated by the first relay when the latter is energized, an intermittent switch included in said auxiliary circuit, a secondary energizing circuit for the second relay closed by the closure of the auxiliary circuit, whereby the auxiliary circuit will remain closed independently of the release of the first mentioned relay-operated contact and will be broken by said switch, and an intermittent switch included in said secondary energizing circuit and operable to break said circuit following the breaking of the auxiliary circuit, said intermittent switches each including rotatable conducting and insulating segments and stationary brushes so arranged that when a brush of the first switch is on a conducting segment a brush of the second switch is also on a con-

ducting segment, the latter being extended beyond the conducting segment of the first switch.

13. In a telegraphic sending circuit having spaced terminals, a relay, a key-controlled primary circuit for operating said relay, a contact operated by the relay for closing the main sending circuit, an auxiliary circuit in shunt with the main sending circuit, a second relay, a contact operated thereby for closing the auxiliary circuit, a primary energizing circuit for the second relay closed by a contact operated by the first relay, secondary energizing circuits for each of said relays closed by contacts operated by the respective relays, an intermittent switch included in said auxiliary circuit and in each of the secondary relay circuits, whereby the auxiliary circuit will remain closed independently of the release of the first mentioned relay-operated contact and will be broken by its switch, said intermittent switches each including rotatable conducting and insulating segments and stationary brushes so arranged that when a brush of the switch in the auxiliary circuit is on a conducting segment, a brush of the switch in the circuit of the second relay is also on a conducting segment, the latter being extended beyond the conducting segment of the first switch and the switch in the circuit of the first relay having its conducting segment arranged opposite to those of the other switches and overlapping the ends of the same.

14. In a telegraphic sending circuit, a relay-operated contact for closing the main circuit, an auxiliary circuit in shunt with the main sending circuit, a relay-operated contact for closing the auxiliary circuit, key-controlled means for operating said relays, and an automatic rotatable switch operable to control said relay contacts and to open said auxiliary circuit on the release of said key-controlled means.

In testimony whereof I have hereunto set my hand in the presence of two subscribing witnesses.

EDWIN S. PRIDHAM.
